(57) **CLAIM**

The ornamental design for a storage container with lid, as shown and described.

DESCRIPTION

FIG. 1 is a front, right, perspective view of a storage container with lid showing our design;
FIG. 2 is a top plan view thereof;
FIG. 3 is a bottom plan view thereof;
FIG. 4 is a left, side view thereof, the right side view being a mirror image of the left, side view;
FIG. 5 is a front view thereof; and,
FIG. 6 is a back view thereof.

The broken lines, which define the bounds of the claimed design, are for illustrative purpose only and form no part of the claimed design.

1 Claim, 2 Drawing Sheets
